UNITED STATES PATENT OFFICE.

MICHAEL W. McARDLE, OF CHICAGO, ILLINOIS.

VIBRATING CUTTER FOR SHEEP SHEARS AND THE LIKE.

Application filed June 11, 1926. Serial No. 115,194.

The purpose of this invention is to provide a vibrating or reciprocating cutter or the like member of a sheep shear of which the shear blade may be a simple flat piece of 5 thin steel die-cut from a sheet, of the proper contour to comprise the desired number and form of shear teeth, such sheet steel member being held flat on the cooperating fixed cutter or comb of the tool, by a body or actuating member adapted to be engaged for 10 actuation by suitable means comprised in the tool for the purpose, and having means for engaging the sheet steel cutting member otherwise than at the edges of the member, 15 whereby said edges may be exposed clear of the actuating member for cooperating shearwise with the edges of the teeth of the fixed shear member or comb.

The invention consists in the features and 20 elements and construction herein shown and described, as indicated in the claims.

In the drawings:—

Figure 1 is a plan view of the vibrating cutter member of a sheep shear constructed 25 according to this invention.

Figure 2 is a plan view of the body or actuating member of such vibrating cutter.

Figure 3 is a plan view of the assembled 30 vibrating cutter shown in operative position on the cooperating fixed cutter or comb of the sheep shear.

Figure 4 is a section at the line 4—4 in Figure 3.

Figure 5 is a section at the line 5—5 on 35 Figure 3.

Figure 6 is a section similar to Figure 5 on a larger scale, showing a detail modification in the form of the shearing edges of the vibrating cutter blade.

40 In the drawings, A represents the cutting member of the vibrating cutter, said member being a perfectly flat piece of steel which is preferably made by cutting by a die a blank from sheet steel, whereby the edges including the shearing edges of the teeth, A¹, A², A³, are directly transverse to both surfaces of the blank, and are thereby adapted for shearing action at both sides, so that this cutting member may be used either side up; and when it becomes dulled at one side, it may be turned over to bring the other corner into service for shearing.

The body member, B, is a metal stamping formed with a peripheral flange, B', con- 55 formed in outline to the form of the cutting

member A, at least throughout the contour of so much of said cutting member as comprises the teeth, A¹, A², A³, and dimensioned for exposing beyond said flange, when the body member is lodged upon the cutting member with the short studs, b, A¹ engaged in the aperture, a of the latter, a narrow marginal portion only of the teeth, A¹, A², A³, a projection of 10/1000", being sufficient.

65 It will be understood that the body or actuating member, A, is adapted for engagement for actuation by the actuating means of the tool, which is usually a vibrating lever terminating for engaging apertures in the 70 vibrating cutter, such apertures being provided as seen in A¹—A¹, in the member A. The vibrating cutter, as a whole is symmetrical about a line through the point of its middle tooth radial with respect to the 75 arc, the vibrating cutter having, therefore, an odd number of teeth. This symmetry of outline adapts the cutting member for being reversed, as above mentioned, to utilize both the corners of shearing edges of the teeth, 80 that is, the lines of intersection of the die-cut edges with both the surfaces of the blank.

85 For some sorts of shearing service, a right-angle shearing corner may be found less efficient than a slightly acute corner, such as would be produced by slightly beveling the edges of teeth; and for providing such bevelled or slightly acute edges without sacrificing the advantage of reversibility of 90 the cutting blade, the edges of the teeth may be milled to form a V-shaped groove therein, as illustrated in the magnified view, Figure 6.

I claim:

95 1. A vibrating cutter for a sheep shear, or the like, comprising a cutting member and an actuating member, the cutting member being thin sheet metal adapted to seat flat on the comb member of the shear, the actuating member being adapted for engagement by the reciprocating means of the shear and being peripherally conformed closely to the outline of the cutting member, and seating thereon along the cutting edges of the latter, 100 said two members having cooperating features for actuating engagement of the cutting member by the other.

105 2. In the construction defined in claim 1, the cutting member being devoid of deflec- 110

tion either upward or downward from its plane, whereby it is equally adapted to be sharpened on either side.

3. In the construction defined in claim 1, the cutting member being die-cut from metal sheet and devoid of deflections from its plane toward either side; whereby it is rendered reversible for utilizing the intersection of either face with the peripheral edge for operating shearwise with the comb teeth.

4. In the construction defined in claim 1, the vibrating blade having an odd number of teeth all radiating in an arc about the axis of vibration and being symmetrical about the middle line of the middle tooth, the lateral teeth of both sides being each rendered

non-symmetrical by having their opposite cutting edges differently inclined to the radial line through the apex, the edge toward the side of the middle tooth being more nearly radial than the outer edge.

5. In the construction defined in claim 1, the cutting member having apertures for engagement by projections from the actuating member, said member having downwardly projecting studs for engaging said apertures for vibrating the cutting member.

In testimony whereof, I have hereunto set my hand at Chicago, Illinois, this 8th day of June, 1926.

MICHAEL W. McARDLE.
